UNITED STATES PATENT OFFICE.

EARL GANNETT CHISHOLM, OF MALDEN, MASSACHUSETTS.

GAME.

Application filed December 1, 1926. Serial No. 151,920.

The invention has relation in general to games, meaning thereby the actual equipment or appliances, and consists in a novel game simulating golf.

The object of the invention is to provide game appliances or equipment of simple character which can be used indoors in an interesting manner, and so as to afford practice in the important part of the playing of golf which is known as putting.

Embodiments of the invention are illustrated in the accompanying drawings, in which latter,—

Fig. 1 is a plan view illustrating certain of the game elements disposed according to one optional arrangement in readiness for use.

Fig. 2 shows, on a larger scale than Fig. 1, a pair of hazards mounted in spaced relation upon a foundation sheet, to form a putting-hole or station.

Fig. 3 shows an alternative arrangement of the pair of hazards of Fig. 2, to form a putting-hole of different characteristics.

Fig. 4 is a view in cross-section of the putting-cup.

In the drawings, 1 designates a convenient supporting surface, which for the purposes of the invention may be regarded as simulating a fairway of a golf course. At 2, 2, etc., are boundaries of the said surface defining the limits within which play is to be confined. Sometimes it will be found advantageous to place the game elements upon the top surface of a rug, in which event the edges of the rug will constitute the boundaries.

At 3, 3, are shown what may be termed hazards, grouped in pairs, the two elements of each pair being spaced apart sufficiently to permit of convenient reception and passage between them of a ball serving for the purposes of the plays. The ball in question is to be driven by the player through or into and from the space or area between a pair of the hazards. I contemplate employing a regular golf ball and a regular putting-iron. The extent of separation of the two hazards of a pair will be sufficient to permit of the insertion of the club or putting-iron between them, as may be necessary in propelling toward the next pair over the surface 1 a ball coming to rest within the space between such two hazards.

The space between the two members of each pair of hazards may be regarded as a

putting hole. The aim in the use of the game will be to cause the ball to pass through or into and from the spaces or openings of the successive pairs of hazards in the predetermined order with the use of the fewest possible strokes.

The pairs of hazards 3, 3, will in practice be disposed variously, at the option of the player or players, upon the surface 1. In most cases, they will be so disposed that the passageways between the respective pairs shall occupy various angular relations with respect to one another, so as thereby to enhance the interest of playing by increasing the difficulties incident to causing the ball to pass into or through the spaces of the respective pairs of hazards in the predetermined succession.

At 4 is a putting cup located in an optional relation with respect to the last pair of hazards, and into which the ball is to be putted after having been entered between the various pairs of hazards in succession.

The hazards shown in the drawings are blocks having the form of right-angled triangles in transverse section, and when associated in a pair to define a putting-hole are preferably disposed as in Fig. 2, namely with proximate vertical faces, and with their oblique plane faces turned in opposite directions away from each other and sloping outwardly down to the surface on which the parts are placed. As associated in a pair, the ball may either be putted into or through the passageway from one end of the latter, or may be caused to roll up one of the sloping plane faces and land in the passageway. As will be perceived, a pair of the said hazards provides a hole into which a ball may be driven in any direction along paths extending along the said surface into or through the passageway between such pair, as well as transversely at various angles with respect to the said passageway, and also one from which the ball may be played as it lies without requiring to be lifted. It is thus a sort of station through which the ball must be passed. Some skill will be requisite in order to cause the ball to drop into the passageway in being played up one of the sloping sides, in order to avoid jumping completely over the passageway.

The blocks of a pair may be independent and unconnected with each other, and simply be placed loosely upon the surface 1, or they may be combined for use through being

mounted upon a suitable foundation sheet, as at 6 in Fig. 2. Usually, however, the blocks will be separate and independent, for convenience in storage and shipment. The

6 surfaces of the blocks may be bare, or the vertical or other surfaces may be covered with suitable material, as cloth, felt, etc.

A game requiring a greater degree of skill may be played with the same component elements and in the same manner, by arranging each of the pairs of hazards in the manner illustrated in Fig. 3. In this arrangement, the blocks 3, 3, will rest upon their bases and will be placed parallel to each other, but 10 their vertical faces will be turned in opposite directions away from each other and their oblique faces will slope inwardly toward each other to bound or define a rectangular space of the same area as is defined by 15 the vertical faces in the other arrangement described hereinbefore. The ball must be putted accurately into either end of this space or passageway in order to enter, and the "hole" thus is approachable only in the 20 general direction of its length. Otherwise than this, the hole and the game is played as outlined above.

The putting cup 4 shown in the drawings is in the form of a flat truncated cone having in its upper portion a recess 7 for the reception of the ball. The conical shape adds to the difficulty of entering the ball into the recess. An advantage in connection with the blocks forming the hazards of the form 25 shown in the drawings resides in the fact that a pair of the said blocks may be produced from an initial wooden blank of rectangular oblong shape, resembling a brick, by sawing the said blank in two on a plane 30 extending the length of the blank and across the diagonal of its end. This single cut produces blocks which have a rectangular cross-section in the direction of their length, and in a transverse direction a cross-section that 35 is a right triangle.

40 What I claim as my invention is,—

1. A game for use with a ball and a propelling club, comprising a supporting surface simulating a fairway, hazards consisting 45 of pairs of blocks respectively triangular in transverse section resting upon their bases upon the said surface with vertical sides facing each other at a distance apart suitable for the passage of a ball between them and 50 with inclined sides extending laterally in opposite directions and constituting sloping ap-

55 proaches to the passageway between the blocks, with the successive pairs constituting consecutive stations of a predetermined course to be traversed by the ball.

2. A game for use with a ball and a propelling club, comprising a supporting surface simulating a fairway, hazards consisting of pairs of blocks respectively triangular in transverse section resting upon their bases 60 upon the said surface with vertical sides facing each other at a distance apart suitable for the passage of a ball between them and with inclined sides extending laterally in opposite directions and constituting sloping approaches 65 to the passageway between the blocks, with the successive pairs constituting consecutive stations of a predetermined course to be traversed by the ball, and with a block providing at the end of such course 70 a putting cup.

3. A game for use in combination with a ball and propelling club, comprising a supporting surface simulating a fairway, hazards consisting of pairs of blocks respectively triangular in transverse section resting upon their bases upon the said surface 75 with vertical sides facing each other at a distance apart suitable for the passage of a ball between them, and with inclined sides extending laterally in opposite directions and constituting sloping approaches to the passageway between the blocks, with the successive pairs constituting consecutive stations 80 of a predetermined course to be traversed by the ball and standing at varied angular relationship to each other.

4. A game for use with a ball and propelling club, comprising a supporting surface simulating a fairway, hazards consisting of 85 pairs of blocks respectively triangular in transverse section resting upon their bases with their oblique faces sloping inwardly toward each other defining an area of the supporting surface to serve as a putting-hole. 90

5. A game for use with a ball and propelling club, comprising a supporting surface simulating a fairway, hazards consisting of pairs of blocks respectively triangular in transverse section resting upon their bases 95 with their oblique faces sloping inwardly toward each other, and forming a station through which the ball must be propelled, the successive pairs of hazards constituting consecutive putting-holes of a predetermined 100 course to be traversed by the ball.

E. GANNETT CHISHOLM.
